UNITED STATES PATENT OFFICE.

WILLIAM P. WOELKE, JR., OF SEATTLE, WASHINGTON.

LIQUID-FUEL REGULATOR.

Application filed October 17, 1924. Serial No. 744,295.

To all whom it may concern:

Be it known that WILLIAM P. WOELKE, Jr., a citizen of the United States, residing at Seattle, in the county of King and State 5 of Washington, has invented certain new and useful Improvements in Liquid-Fuel Regulators, of which the following is a specification.

This invention relates to an improvement 10 in gasoline feed means for automobiles and like vehicles, wherein provision is made for feeding the gas from the storage tank to the carbureter under traveling conditions where the level of the carbureter is above 15 that of the outlet of the tank.

The invention is particularly directed to providing the closing cap of the filling port of the tank with means to permit the application to such cap of an air pump, whereby 20 pressure may be introduced onto the body of gasoline within the tank, to cause said gasoline to flow under pressure to the carbureter notwithstanding the higher level of the latter.

25 The invention is more particularly concerned with the means for closing the air inlet against the escape of the air pressure, and the provision in such closing means of a construction whereby the accumulation of 30 dirt or other refuse, tending to prevent a proper seating of the valve, will be entirely eliminated.

The invention is illustrated in the accompanying drawings, in which:

35 Fig. 1 is a view in elevation of the improved cap, showing air pressure hose connected thereto.

Fig. 2 is a transverse sectional view of the same, a closing cap being shown applied.

40 Fig. 3 is a bottom plan view.

The present invention consists in providing the usual cap 1 for closing the filling port 2 of the gasoline tank 3, with a central bore 4 extending through the cap and 45 through an upstanding central nipple 5 integral with the cap. The upper end of the nipple is threaded at 6 for the reception of the usual connecting terminal 7 of the hose

8 of an air pump, the threaded extension 6 being likewise adapted for the reception of 50 a closing cap when the pump is not in use.

The bore 4 is formed to present a valve seat 9, with which a ball valve 10 is adapted to cooperate to seal the bore against the escape of pressure from within the tank. 55 Heretofore in structures of this character, the ball has been held in place by upsetting the edges of the bore, but these upset edges tend to retain any dirt or refuse which may enter through the bore in a position to 60 interfere with the proper operation of the valve, and thus eventually defeat the very object of the invention. For the purposes of the present invention, the lower surface of the cap is formed with an annular flange 65 11, concentric with the bore 4, this flange being diametrically slotted at 12 to receive a fine wire 13 following the application of the ball valve in position in the bore. The wire 13 is forced into the slits 12 and underlies 70 the valve to prevent the escape of the same from the bore 4, while it is obvious that any dirt or refuse passing through the bore 4 will immediately fall past the wire and thus be discharged from the bore and the latter 75 maintained in a cleanly condition to insure a proper operation of the valve.

Claim:

A recessed filler cap for automobile tanks, having a central bore extending substantially throughout the depth of the recess, means for removably connecting a pressure medium in line with said bore, a valve operative in the bore to prevent fluid passage in one direction, a flange on the inner surface of the cap concentric with the bore and extending slightly below the inner surface of the cap, said flange being diametrically slotted with the slots opening through the lower edge of the flange, and a wire secured 80 in said slots transverse the flange and directly underlying the valve, the wire being spaced from the bottom surface of the cap. 85

In testimony whereof I affix my signature.

WILLIAM P. WOELKE, JR.
